UNITED STATES PATENT OFFICE.

ERNEST J. LORING, OF SOMERVILLE, MASSACHUSETTS, ASSIGNOR TO THE LAMSON COMPANY, OF BOSTON, MASSACHUSETTS, A CORPORATION OF NEW JERSEY.

PNEUMATIC-DESPATCH-TUBE APPARATUS.

1,258,422.

Specification of Letters Patent.

Patented Mar. 5, 1918.

Application filed July 19, 1916. Serial No. 110,218.

To all whom it may concern:

Be it known that I, ERNEST J. LORING, a citizen of the United States, residing at Somerville, in the county of Middlesex and 5 State of Massachusetts, have invented certain new and useful Improvements in Pneumatic-Despatch-Tube Apparatus, of which the following is a specification.

This invention relates to pneumatic despatch tube apparatus and more particularly to what is known as a pressure system.

One of the principal objects of my invention is to provide a novel means for controlling the operating pressures in a plurality 15 of transit tubes of different lengths whereby to insure an adequate effective pressure in each for the proper transmission of carriers therethrough.

Another object is to construct said pressure controlling means so as to reduce noise and vibration of the apparatus substantially to a minimum.

Still another object is to so constitute the apparatus as to enable it to meet the exacting service conditions incident to such institutions as stock exchanges and the like.

These and other objects of my invention will be hereinafter referred to and the novel combinations of means and elements whereby 30 said objects may be attained will be more particularly pointed out in the claims appended hereto.

In the accompanying drawings which form a part hereof and in which like reference characters designate like parts throughout the respective views, I have exemplified a preferred embodiment of the invention, but as I am aware of various changes and modifications which may be made herein 40 without departing from the spirit of said invention, I desire to be limited only by the scope of the claims.

Referring to the drawings:

Figure 1 is a somewhat diagrammatic representation of a system constructed in accordance with the principles of the invention, viewed in side elevation; certain parts being broken away or shown in section for purposes of illustration.

Fig. 2 is a plan view of a part of said system, showing the disposition of the stations and of different lengths of transit tubing connecting said stations.

Fig. 3 is an enlarged partial section of a combination pressure-controller and silencer 55 used in the system.

Fig. 4 is a detail front elevation of said pressure-controller.

Fig. 5 is a section taken on line V—V of Fig. 4. 60

Fig. 6 is a front elevation of a modification of said controller, differently apertured from the first; and

Fig. 7 is a section of the same taken on line VII—VII of Fig. 6. 65

The transmission tubes 1—2—3—4, when the system is intended for use in, for example, a stock exchange, are preferably, although not necessarily, pressure tubes,—the compressed air for propelling the carriers 5 70 therethrough being supplied in this case from a drum 6 into which the air is delivered from a blower or pump 7 through a supply pipe 8, the blower preferably being driven by an electric motor 9 or the like. 75

The air emerging from the drum passes through a nipple or pipe section 10 and thence through a combination flow-silencing and pressure-regulating device consisting of a retaining sleeve 11 and a multiple-nozzled 80 plate 12 hereinafter more fully described.

The preferably continuously flowing air then passes through a spacing nipple or pipe 13 which separates the controller from the despatching terminal 14; there being one of 85 these at each of the trading or clerk stations A—B—C—D from which carriers may be despatched, past the corresponding valves 14', to a delivery desk.

At this latter, a novel terminal arrangement is employed to economize space and facilitate the expeditious handling of the incoming carriers.

Carriers emerging from, for example, the first of a pair of tubes 1, pass around the deflector 15, which may be inexpensively constructed of bent sheet metal the upper side 15' of which forms the receiving shelf of the companion terminal 16 in the upper tier which receives carriers from the tube 2. 95

After the respective carriers have partly lost their momentum during their passage around the deflecting under surfaces of the parts 15 or 16, they fall into a receptacle or trough 17 from whence they are removed 105 as promptly as possible by the operator or

operators at the delivery desk; said receptacle preferably being common to the various terminals in the respective tiers of the same.

If the system be one in use in a stock exchange, the brokers or their clerks will usually be at their stations A—B—C, etc., and it will be understood that while but four tubes and despatching stations have been shown, in practice this number will be very much larger, so that there may be as many as twenty-five or more outgoing tubes. The incoming or return tubes have not been shown, to avoid confusion. As applied to a stock exchange, my improved tube system is preferably of the pressure type, compressed air being delivered from a single supply, such as the extended reservoir drum 6, to a considerable number of tube lines of various lengths each of which, as shown, normally discharges at, for example, the central desk and each with a certain fixed rate of flow. In some stock exchanges, it is regarded as desirable on certain service, to coordinate the various lines to the end that carriers may be transmitted between A and E, and between B and E, etc., with substantially an equal period of transmission from each of the broker's stations, since otherwise one broker would be unduly favored over another.

One plan for equalizing the time of transmission would be to make all of the tubes of equal length; but this would not only involve useless waste of tubing but even then the bends or turns in some of the tubes would be apt to be sharper than the bends in others and again a slight but appreciable difference in the times of transmission would result.

Again, the pressure in the drum must be sufficient to properly transmit carriers through the longest line but for the shorter lines wherein the flow resistance is obviously less, if some provision be not made to throttle down the air flow there will of course be a tendency for the heaviest current of air to flow through the shortest line. In some cases it is desirable to produce equal rates of flow in all of the lines, but if the system is to be one such as that just mentioned, this cannot be permitted, but rather, the air flow through the longest tube should be the greatest and the rate of flow through the shorter tubes correspondingly less, to effect the transmission of carriers through the various lines in equal times.

Whether equal rates of flow are desired or equal transmission times, therefore, some resistance affording means must be provided to control the outrush of air from the drum. I have attempted to provide for this resistance by means of sliding gates and butterfly vanes, but the surfaces of such gates are not favorably arranged for the quiet passage of air at the high velocities which nec-

essarily accompany marked constrictions of the flow. I have, however, discovered that if the resistance is applied by means of a constricting nozzle or nozzles in the line of flow,—the surfaces in contact with the high-velocity air, being fixed, may be arranged in accordance with the results of experiments which I have conducted, to afford the degree of quietness of operation required.

For usual conditions where the pressure difference on the respective receiving and delivery ends of the nozzle is not great, or in other words where this difference is materially less than the critical value

$$\left(\frac{p_1 - p_2}{p_1} = .48 \text{ for air} \right),$$

I have found that the most favorable form of nozzle aperture is a short straight throat or bore with an approach, the curves in which are on easy flow lines. For maximum quietness of operation it is important that the stream be well supported by the walls of the nozzle and any sudden constriction or over-expansion should be avoided. Indeed, even a slight rounding of the flow-directing walls of the nozzle orifice at the discharge end of the latter is objectionable.

When air flows through a nozzle such as above described, if the axis of the nozzle orifice be substantially coincident with the axis of the tube in which said nozzle is disposed, a partial vacuum is formed adjacent the walls of the tube and just beyond the nozzle, and it is probably this vacuum which causes a turbulence of flow which creates a noise.

I have found that this effect may be counteracted by surrounding the central nozzle orifice by a ring of smaller apertures of the same type, as shown in Figs. 6 and 7 wherein in the nozzle-plate 12' has a relatively large central orifice 12^a around which are located a number of secondary openings 12^b, similar in general contour but considerably smaller in diameter.

In Figs. 4 and 5 I have shown an equivalent nozzle-plate 12 which on account of its simpler shape is to be preferred; the large central orifice being in this case replaced by a series of smaller ones 12^c distributed with approximate uniformity over the partition or plate which I have termed in general a nozzle-plate but which may perhaps be more aptly termed a "multiple nozzle".

If such a series of nozzle apertures be grouped in a more compact unit at the center of the tube, the result approaches that afforded by a single relatively large nozzle orifice, and I have ascertained by experiment that the fewer the openings and the larger the size thereof, the more intense is the rather deep pulsatory noise produced; while if the holes be relatively quite small and the number thereof correspondingly in-

creased, again the noise becomes objectionably pronounced,—it this time, however, being more in the nature of a hiss.

For a given size and shape of orifice and 5 a given difference in pressures upon opposite sides thereof, a definite and predetermined flow of air will occur therethrough and a nozzle-plate such, for example, as that designated 12, will dependably afford just 10 the flow of air desired through a given tube; there being preferably one such plate in each line extending from the drum, and the number of orifices and the relative sizes thereof, with preferably corresponding differences 15 in thickness of the plates (especially where considerable differences in the lengths of the respective lines occur), will determine the flow of air through the respective lines and permit of the flows being 20 made equal as to quantity or as to their ability to cause the transmission of carriers through the respective lines in a given and common interval of time.

The pressure in the drum is preferably 25 normally substantially constant, while the normal pressure against the discharge side of a given plate will be the resistance which the tube corresponding thereto offers to the flow of that particular volume of air. This 30 resistance is known or may be readily determined and therefore as conditions on both sides of the plate are definite and known or ascertainable, the multiple nozzle will, for a constant-pressure supply, deliver a constant 35 volume to the line and the total orifice area necessary for a desired volume of air may be predetermined from the supply pressure and the length and size of the line, and hence may be definitely specified.

40 A further advantage of the converging-walled stream-line surfaced nozzle-aperture, 12°, preferably used, resides in the fact that the co-efficient of discharge is nearly unity, there being very little contraction of the 45 jet (and consequent constriction of the flow) emerging from an orifice.

Again, since said co-efficient is thus nearly 50 unity, the flow is but little affected by moderate changes in pressure, which means that 55 results may be predicted with more certainty under varying conditions.

If it be desired to transmit carriers through 60 the various lines, or a number of them, in equal times, the volume of air delivered 65 through the longer lines will be correspondingly greater than for shorter lines and the flow resistance will again obviously be substantially in proportion to the volume and length of line. The nozzle plates of 70 such longer lines will differ from those of the shorter lines to accommodate the increased flow; but once a plate is set in position in a given line, the volume and rate of 75 flow of the air through that line is substantially fixed and a carrier of normal weight

and size inserted at station A, for example, will arrive at station E a certain and predetermined time thereafter.

To prevent tampering with the nozzle plates, especially in stock exchanges, they 70 are preferably placed, as shown, between the pressure drum 6 and the connection 13 which delivers to the inlet or despatching terminal 14; so that during replacement of the inlet, in the event of trouble therewith, neither by 75 accident nor from evil intention can the nozzle plate of such line be altered or altogether omitted whereby to change the pressure relations on all lines from that particular drum.

By thus employing a non-adjustable pressure regulating device and locating the same 80 in a position which is normally inaccessible, all temptation for meddling with and consequent derangement of the system is removed 85 and the system is permitted to operate as designed.

In practice, a limited number of different 90 types of nozzle plates are manufactured, providing for variations in area, etc., of the apertures thereof; these plates being rated 95 by pressure difference at a certain standard rate of flow. If equal volumes of air are to pass through the tubes of a system, the plate for each tube is selected so that the 100 sum of the pressure drop in the corresponding tube, its inlet and multiple nozzle, will be substantially equal to the pressure in the supply drum; so that the pressure of the air emerging from said tube at its delivery end, 105 will be approximately that of the atmosphere.

If equal times of transmission are to be provided for, then the shortest tube may have its nozzle-plate apertured to provide 110 sufficient resistance to supplement those of the line, to discharge air at atmospheric pressure or but little thereabove; while the longer tubes, in proportion to their respective increases in length, will have their multiple nozzles gaged to each offer sufficiently less resistance to cause the requisite increase in volume and pressure of the air flowing through such tubes to speed up the carriers propelled thereby, to enable such carriers to 115 negotiate the tubes in times substantially common to all.

In conclusion, two features of importance 120 may be noted,—first: That the provision of the multiple-nozzled plates or elements in the tubes, or the equivalents thereof, in addition to affording quietness of operation and definite control of the air-flows through the various tubes, offers the advantage that if the load in a carrier be such as to impede 125 its progress and such carrier slows down or tends to stop in the line, there is instantly a tendency for the pressure back of the carrier to build up toward that in the drum and thereby to propel said carrier,—at least 130

momentarily or until it has again resumed its normal speed,—more vigorously toward its destination.

Second: the multiple-nozzled device has no movable or loose parts, such as a gate or vane, to rattle and constitute a source of objectionable noise; nor has it relatively sharp edges such as are commonly present in gates and valves and past which the air current would flow with a whistling or hissing sound.

Having thus described my invention what I claim is:

1. A pressure pneumatic tube system comprising a series of transit tubes through which carriers are propelled by compressed air, a despatching inlet for each of said tubes, a drum constituting a source of pressure fluid for said tubes, connections between said inlets and said drum, and a combination silencing-device and pressure-regulator for each of said connections for offering a predetermined resistance to the air flowing into the corresponding tube, the comparative resistance of each device to the air flow

passing the same being substantially inversely proportionate to the flow resistance of the tube corresponding to said device.

2. A pressure pneumatic tube system comprising a plurality of transit tubes respectively extending between a delivery desk and a plurality of stations, means for introducing carriers into said tubes at said stations, an extended drum for supplying compressed air to said tubes to propel said carriers, said drum extending in adjacency to each of said stations, and means to substantially silently control the exhaust of air from said drum into said tubes, said controlling means comprising a plurality of co-acting regulating devices, one for each of said tubes, said devices being apertured to maintain definitely related normal flows of air through the tubes proportioned to the lengths thereof.

In testimony whereof I have affixed my signature, in the presence of two witnesses.

ERNEST J. LORING.
